(57) **CLAIM**

The ornamental Design for a chair, as shown and described.

DESCRIPTION

FIG. 1 is a perspective view from the front and to one side of the chair.

FIG. 2 is a perspective view from the rear and the other side of the chair of FIG. 1.

FIG. 3 is a front elevational view of the chair of FIG. 1.

FIG. 4 is a side elevational view of the chair of FIG. 1. The other side of the chair is a mirror image of this view.

FIG. 5 is a rear elevational view of the chair of FIG. 1; and, FIG. 6 is a top plan view of the chair of FIG. 1.

The base of the chair and the seat of the chair which are shown in broken lines do not form part of the design.
